UNITED STATES PATENT OFFICE

HAROLD L. SEAVERS AND PHILLIP G. BERNSTEIN, OF YORK, PENNSYLVANIA

PRESSER FOOT

Application filed October 21, 1930. Serial No. 490,305.

This invention aims to provide a presser foot for a sewing machine, so constructed that a line of stitching may be made in accurate, parallel relation to the edge of the material, or to the edge of a seam, the device being capable of being used on sewing machines of many kinds, and under many conditions which call for an accurately formed, straight edge on the material, disposed in parallel relation to a line of stitching. The invention aims, moreover, to provide a device of the class described which can be used in the ordinary way on a flat surface when there is no occasion for locating the line of stitching accurately in parallel relation to an edge in the material.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows in top plan, a device constructed in accordance with the invention, a part of the sewing machine proper appearing in section;

Figure 2 is an elevation;

Figure 3 is a bottom plan;

Figure 4 is a section on the line 4—4 of Fig. 2;

Figure 5 is a view like Figure 4, but showing the auxiliary presser foot raised, as occurs in sewing on a flat surface, Figure 4 illustrating the position of the auxiliary presser foot when sewing along an edge;

Figure 6 is a section on the line 6—6 of Figure 2, the parts being arranged as they will appear when the device is used to sew along an edge;

Figure 7 is a view like Figure 6, but illustrating the parts as they will appear when sewing on a flat surface;

Figure 8 is a rear elevation;

Figure 9 is a rear elevation wherein the slide and attendant parts have been separated from the sewing machine;

Figure 10 is a perspective view of the slide 55 and the parts which are attached to it;

Figure 11 is a perspective view of the retainer or angle bracket;

Figure 12 is a perspective view of the main presser foot and the part whereon it is mounted.

The numeral 1 marks a support, which may be the upright bar of the sewing machine. Figure 12 shows that the bar 1 has a longitudinal groove 2 in one side, this groove forming a rib 30 and a rib 38 which are parallel to each other, the ribs 30 and 38 being of approximately the same width from front to back, as disclosed in Figure 1.

At its lower end, the bar 1 has a laterally 70 and downwardly projecting offset 3 (Figures 12 and 2) provided with ears 4 between which extends an upstanding flange 5 on a main presser foot 6. The main presser foot 6 has a needle hole 7 (Figures 1 and 2) in its inner edge. The outer end of the presser foot 6 is turned upwardly, as usual, and as denoted by the numeral 8. A pivot element 9 is mounted in the ears 4 of the offset 3 of the bar 1 and extends through the flange 5 of 80 the main presser foot 6, the main presser foot having a slight up and down swinging movement on the pivot element 9, this movement being limited, however, because, as shown in Figure 12, the heel 10 of the presser foot 6 85 extends backwardly underneath the offset 3.

A slide 11, shown in detail in Figure 10 of the drawings is mounted for vertical reciprocation on the bar 1. The slide 11 has a longitudinal rib 12 which moves in the groove 90 2 of the bar 1. The rib 12 is located at one corner of the slide 11, as Figure 10 will show, and in the opposite corner of the slide 11 there is a groove 37 which receives the rib 30 of the bar 1, as shown in Figure 1, the groove 37 defining a wing 31 in the slide, the wing 31 overlapping the outer surface of the rib 30. Figures 2 and 10 disclose that the slide 11 has an outwardly projecting finger 14 supplied in its upper edge with a seat 15.

On the lower end of the slide 11 there is an offset 16 which, like the offset 3 of the bar 1, projects laterally and downwardly, the offset 16 being disposed at the side of the offset 5 3, as shown in Figure 1. The offset 16 has ears 17 between which extends an upstanding flange 18 on an auxiliary presser foot 19 (Figure 10) located at the side of the main presser foot 6, (Figure 6), the auxiliary presser foot 19 10 having a rounded end 20 so that the work can pass under the auxiliary presser foot readily. A pivot element 21 is mounted in the ears 17, and in the flange 18 of the auxiliary presser foot 19. The auxiliary presser foot 15 19 has a slight up and down swinging movement on the pivot element 21, but this movement is limited because, as shown in Figure 2, the heel 40 of the auxiliary presser foot extends beneath the offset 16 on the slide 11, 20 this being shown also, in Figure 10 of the drawings.

A guide block and spacer 22 (Figures 1 and 8) is disposed against the outer surface 23 (Figure 12) of the rib 38 on the bar 1, and 25 the slide 11 reciprocates in engagement with the guide block and spacer as is shown in Figure 1. The guide block and spacer 22 is an extremely useful article or part of the device, since it enables the auxiliary pressure foot 19 30 and parts which carry it, to be used on machines of many different makes. A portion of the rear edge 24 (Figure 1) of the slide 11 engages the inner surface of the guide block and spacer 22.

35 In Figure 11 there is shown a retainer or angle bracket 25 that appears, also, in many other figures of the drawings, for instance, in Figures 1 and 2. The retainer or angle bracket 25 comprises a first flange 26 and a 40 second flange 27 disposed at right angles to each other. The flange 27 extends along the outer surface of the slide 11 and along the outer surface of the spacer 22. The flange 26 extends along the inner longitudinal surface 45 of the bar 1. The part 25 is called a retainer, because it holds the slide 11 on the bar 1 for reciprocatory up and down movement. The retainer 25 is held on the bar 1 by securing elements 28 which pass through 50 the flange 26 of the retainer and enter the bar 1.

The guide block and spacer 22 is held between the rib 38 of the bar 1 and the flange 27 of the retainer 25 (Figure 1) by two securing elements 29 and 32 that go through the flange 27 and through the guide block and spacer, the said securing elements entering the bar 1. The securing elements 32, 29 and 28 preferably are screws.

55 In addition to their functions as retainers for the guide block and spacer 22, the securing elements 29 and 32 have another function, in that a spring 33 is engaged around the securing element 29. The spring 33 has a 60 downwardly extended arm 34 (Figure 2)

which bears against the securing element 32 and is held against the flange 27 by the end of the securing element 32. The spring 33 has an inwardly extended arm 35 which is received in the seat 15 (Figure 10) of the 70 finger 14 on the slide 12, the finger 14 projecting outwardly (Figures 2 and 5) through an elongated opening 36 (Figure 11) formed in the flange 27 of the retainer 25. Figures 11 and 2 show that the flange 27 of the retainer 25 is cut away to form a recess 39 at its inner corner, this recess receiving the upper rear corner 41 (Figure 2) of the offset 16 on the slide 11, as the slide moves upwardly 75 against the action of the arm 35 of spring 33. 80

The arm 35 of the spring 33, acting on the finger 14 of the slide 11, tends to carry the slide and the auxiliary presser foot 19 downwardly, so that the lower surface of the auxiliary presser foot is a little below the lower surface of the main presser foot 6, as shown in Figures 2, 4 and 6.

The numeral 42 marks a piece of material, presenting an edge 43. This edge 43 is run along the inner surface of the presser foot 19, 90 as shown in Figures 6 and 4, and it will be obvious that a sewing machine needle (not shown) working through the needle hole 7 of Figures 3, 2 and 1, will cause a line of stitching to be made in the material 42, in 95 parallel relation to the edge 43, the edge 43 being turned out smooth and even. The bar 1 can be carried down in the usual way, so that the lower surfaces of the presser feet 6 and 19 will be in the same plane (Figures 7 100 and 5) and, then, the machine may be used in the ordinary way on a flat piece of material 44.

Having thus described the invention, what is claimed is:

The combination with a member of a sewing machine, carrying a main presser foot, of a slide mounted to reciprocate on said member and provided with an auxiliary presser foot cooperating with the main 110 presser foot, the slide outstanding with respect to said member, a retainer on said member and holding the slide on said member for reciprocation, spring means for depressing the slide to cause the auxiliary presser foot 115 to extend below the main presser foot and present a guiding edge, a combined spacer and guide for the slide, removably disposed between the retainer and said member, and a holding device keeping the spacer and guide in place and passing through the retainer, the spring means being mounted on the holding device.

In testimony that we claim the foregoing as our own, we have hereto affixed our signatures.

HAROLD L. SEAVERS.
PHILLIP G. BERNSTEIN.
